UNITED STATES PATENT OFFICE.

HENRY JOHN QUINCY, OF BROOKLYN, NEW YORK, ASSIGNOR OF ONE-HALF TO
FREDERICK J. QUINCY, OF BROOKLYN, NEW YORK.

BEDSTEAD.

1,075,158.

Specification of Letters Patent.

Patented Oct. 7, 1913.

Application filed July 19, 1913. Serial No. 779,888.

To all whom it may concern:

Be it known that I, HENRY J. QUINCY, a citizen of the United States, residing at Brooklyn, in the county of Kings and State of New York, have invented certain new and useful Improvements in Bedsteads; and I do hereby declare the following to be a full, clear, and exact description of the invention, such as will enable others skilled in the art 10 to which it appertains to make and use the same.

This invention relates to improvements in bedsteads and has for its primary object the provision of a bedstead in which the spring 15 frame is detachably connected to blocks carried by the head and foot posts in a novel manner.

Another object of the invention resides in the provision of a novelly constructed spring 20 frame which may be lengthened or shortened so as to regulate the tension of the springs.

With these and other objects in view, as will become more apparent as the description proceeds, the invention consists in certain 25 novel features of construction, combination, and arrangement of parts, as will be hereinafter described and claimed.

For a complete understanding of my invention, reference is to be had to the following description and accompanying drawings, in which—

Figure 1 is a side elevation of my improved bedstead, Fig. 2 is a vertical transverse sectional view looking toward the head 35 of the bed, Fig. 3 is a detail perspective view of one of the corner fastenings, and, Fig. 4 is a section taken on the plane of line 4—4 of Fig. 1.

In the preferred embodiment of my invention, I provide a bedstead having the head and foot pieces 5 and 6, respectively, and a spring frame, generally designated 7, which serves to support the head and foot pieces in their proper positions.

The head and foot pieces are of essentially similar construction and include the vertical posts 8 and 9. A laterally extending rectangular block 10 is formed upon each post and is provided with a vertical 50 groove or socket 11, which extends entirely therethrough and which opens on the outer face thereof. The blocks carried by the posts extend toward the transverse center of the bedstead and the blocks upon the head

posts are opposed to those upon the foot 55 posts.

The spring frame comprises end bars 12 which are preferably formed of angle iron and which are apertured, as indicated at 13, to permit the attachment of the spring 14. 60 The lower edges of the vertical sides 15 of these angle bars rest upon the blocks 10 and are supported thereby. Angular side plates 16 are integrally formed upon the ends of the bars 12 and depend therefrom. These 65 side plates are disposed upon the outer faces of the blocks 10 and have portions 17 which extend longitudinally beyond the inner ends thereof. As clearly shown in Fig. 1, the lower edges 18 of the side pieces are disposed in a plane below the lower faces of the supporting blocks.

The connection between each block and the corresponding side piece 16 is formed by a somewhat dovetailed tongue or projection 75 19 which is rigid with the side piece and which is received within the socket 11.

Side bars 20 which are formed with right hand threads upon one end and left hand threads upon the other end, are received 80 within threaded sockets 21 formed integrally with the inner faces of the side pieces upon the extensions 17. It will be seen that the side bars may be rotated so as to vary the distance between the end bars 12 85 and thus change the tension upon the springs 14. This feature of my device is of importance as it allows the springs to be tightened from time to time.

When the bedstead is assembled the end 90 bars rest upon the blocks 10, the side pieces engage the outer faces thereof, and the sockets 21 abut against the inner ends of the bars. This arrangement of the parts cooperates with the projections 19 and the 95 grooves or sockets 11, to provide a very rigid and strong structure. The bedstead may be easily taken apart by removing the spring frame from engagement with the blocks 10.

From the foregoing description taken in connection with the accompanying drawings, it will be evident that I have provided a novelly constructed bedstead of extremely simple and strong construction, consisting 105 of a small number of parts which are easily assembled.

It is to be understood that while I have

shown and described the preferred embodiment of my invention, I do not wish to be limited to this exact construction, combination, and arrangement of parts, but may 5 make such changes as will fall within the spirit and scope of the invention.

Having thus described my invention, what I claim is:—

A bedstead including head and foot pieces, 10 supporting blocks formed upon the same and extending toward the transverse center of the bedstead, said blocks being rectangular in shape and formed with vertical sockets opening upon the outer faces thereof, a 15 spring supporting frame including end bars which rest upon the supporting blocks, side pieces formed upon the extremities of the

end bars and engaging the outer faces of the supporting blocks, said side pieces extending below the supporting blocks and projecting longitudinally beyond the inner ends thereof, projections formed upon the side pieces for reception within said sockets, internally threaded sockets rigid with the inner faces of the side bars and abutting 20 against the ends of the supporting blocks, and side bars threaded into said last mentioned sockets to connect the end bars.

In testimony whereof I affix my signature in presence of two witnesses.

HENRY JOHN QUINCY.
